UNITED STATES PATENT OFFICE.

LOUIS N. D. WILLIAMS, OF OGONTZ, PENNSYLVANIA.

TRANSFER MECHANISM FOR KNITTING MACHINES.

Application filed May 10, 1923. Serial No. 637,955.

To all whom it may concern:

Be it known that I, LOUIS N. D. WILLIAMS, a citizen of the United States, residing at Ogontz, county of Montgomery, State of Pennsylvania, have invented certain new and useful Improvements in Transfer Mechanism for Knitting Machines, of which the following is a specification, reference being had to the accompanying drawings.

10 My invention relates to knitting machines, especially to rotary knitting machines, and is, more specifically speaking, directed to improvements in such machines for facilitating transfer of fabrics from one machine to another.

As is well known to those skilled in the knitting arts, the operation of fabric transfer has heretofore always been attended by the possibility of stitch dropping, and this 20 is especially true when the fabric produced by a machine is to be transferred from the needles of the latter to a transfer device with individual stitch engaging means, so that it may be again transferred to another machine for further work to be done upon it. A step illustrative of the foregoing is practiced for example in the manufacture of hosiery when a stocking top is transferred from the producing machine to another designed to knit the leg and foot in integral 30 continuation of the top; and again, in transferring the completed blank to a looping machine, such as shown and described in a Patent No. 1,315,064 granted me under date of September 2, 1919, for closure of its toe pocket.

The main object of my invention is to enable all operations necessary or desirable to the consummation of perfect transfer of 40 knitted fabrics to be effected automatically, these operations to include enlarging or dilating of the loops of the terminal course of the fabric in preparation for better reception of the points of a transfer device; bodily displacing the fabric from the cylinder 45 of the producing machine to insure its retention by the transfer device; clamping the fabric to the transfer device; and finally dislodging the transfer device, with the fabric clamped thereon, from the knitting needles so that said device can thereafter be readily removed from the machine without danger of stitch dropping.

How this desideratum may be attained, 55 together with other subsidiary objects and their attendant advantages, will become

readily apparent from the detailed description which follows of a typical embodiment of my invention; while the appended claims clearly define the scope of my invention in 60 so far as it comes within my present knowledge.

Referring to the drawings, Fig. I is an illustration in elevation of a circular stocking knitting machine convenient for the purposes of my invention, certain portions thereof being broken away and in section to show some of the important details which would otherwise be concealed.

Fig. II is a partial cross section of the machine taken as indicated by the arrows II-II in Fig. I showing the control mechanism for certain of the instrumentalities which cooperate in facilitating fabric transfer.

Fig. III is a view similar to Fig. II, though somewhat more condensed, showing a latch member of the control mechanism aforesaid in a locked position.

Fig. IV is a detail sectional view of the 80 needle cylinder showing the manner in which the needle circle is spread for the purpose of facilitating application of the transfer device, and the terminal loops of the fabric at the same time slightly enlarged 85 or dilated for better reception of the points of said transfer device; and

Figs. V, VI and VII are detail views 90 showing successive positions of the transfer device relative to the needle cylinder during transfer of the fabric in accordance with my invention.

In these illustrations, the needle cylinder is indicated at 1, and shown as rotatably mounted in the overhanging portion 2 of the bed plate 3 of the machine, said bed plate being secured to the top of a supporting and housing framework 4. This framework, it will be observed, affords bearings 5, 5 for the main drive shaft 6 of the machine which carries the usual drive pulleys, whereof one is indicated at 7. The drive of the shaft 6 is translated to produce either rotary or oscillatory motion of the needle cylinder in a well known manner, through various gear connections generally shown in the drawings, and is determined by shifting of a clutch collar 8 on said shaft 6. This clutch collar is engaged by a shifter arm 9 and is controlled by the main pattern drum 10 of the machine indicated by the numeral 10, the latter being mounted upon a counter-

shaft 11 journalled in appropriate bearings also of the frame 4. The machine is further equipped with an auxiliary pattern drum 12 which is rotated from the counter-shaft 11 through the medium of interposed intermeshing spur gears 13, 13. As best shown in Figs. IV to VII, the needle cylinder 1 is provided with longitudinally extending peripheral grooves 15 for vertical guidance of the needles indicated at 16. Web holders 17 cooperate with the needles to form fabric stitches in a well known manner, and are guided for horizontal reciprocation relative to the needles in radial grooves of an annulus 18 secured about the top of the cylinder 1. A cap ring 19, sur-mounted upon the annulus 18, carries the necessary cams for actuating the web holders. The needle actuating cams are contained in a shell 20 shown as surrounding the lower portion of the cylinder 1, and have a suitable control (not shown) associated with them for needle leveling. Yarn is directed to the needles by interchangeable feeds 21 carried by the annular latch guard indicated at 22, said guard being pivotally mounted so that it may be swung rearward, as considered in the illustration, and out of the way when transfer is to be effected. The fabric produced by the machine is received and protected in a tube 23 which serves as an axial prolongation of the needle cylinder, said tube depending from the bottom of the overhang 2 whereto it is secured in an approved manner.

The parts thus far described are such as ordinarily found in standard types of stocking-ordinarily found in standard types of stocking-knitters, and the brief outline given will suffice to make clear their relation to the features novel to my invention, and these will now be taken up in detail. Confining attention for the time being to Figs. IV, V, VI and VII of the drawings it will be observed that within the top of a needle cylinder 1, is an annulus 25, the same being properly configured for maintenance against lateral displacement, while adapted for slight axial movement relative to the cylinder, and appropriately slotted to assist guidance of the web holders 17. About midway of its height, said annulus has a sloping, or more accurately speaking, a conical peripheral surface 26, which, when the annulus is drawn downwardly, acts as a wedge against an expandible, helical spring band 27. This band is in turn, operative upon the needles to flex them simultaneously outwardly and thus to expand the needle circle as shown in Fig. IV in order to facilitate application of a transfer device, such as generally indicated by the numeral 28 in the drawings, to the needles in a manner to be more fully explained later. The said transfer device, it will be observed, comprises a circular series of stitch or loop engaging instrumentalities

in the form of points 29, and in subsequent description, will, for convenience of better distinction, be referred to simply as the "point ring". The points 29 are anchored in a head 30 constituting a part of the shell 31 of the ring, and correspond in number and in spacing to the needles of the machine. In the case of transfer of completed stockings to a sewing machine for closing of the toes, the ring 28 may be split or divided after the manner shown and described in the patent to which reference has already been made. The transfer ring 28 is further provided with an annular member 32 characterized by radial projections 33 that extend outwardly between the points 29, and which is axially shiftable relative to the shell 31 under guidance of pins 34 traversing apertures in the head 30. The pins 34 protrude beyond the head 30 and afford attachment for a circular pressure plate whereby the member 32 may be actuated from above. Said member 32 functions in a dual capacity, in the first instance acting to effect registry of the needles of the machine and the points 29 to ensure positive alignment between them during application of the ring for reception of the fabric, and, in the second instance, acting as a stripper when the fabric is to be doffed from the ring in subsequent transfer to another machine. Since the first function alluded to is the one pertinent in the present connection, the member 32 will, in further description and in the claims, be termed the "registering and aligning means."

The office of shifting the wedge annulus 25 is relegated to a sleeve 36 disposed for vertical axial movement within the needle cylinder 1, and formed at its top with an outwardly projecting circumferential flange 37 designed to overlap said annulus. This flange 37, is slotted in correspondence with the web holder slots in the annulus 25, and it is to be especially noted, extends into close proximity to the needle shanks, so as to underlie the loops or stitches "S" of the terminal course of the fabric indicated conventionally at "F". Downward movement of the fabric into the needle cylinder 1, is eased by provision of a flare 38 adjacent the top or mouth of the sleeve 36. The latter will again be referred to in subsequent description of another office which it performs, and also in connection with the means whereby its movements are induced and controlled.

For the purpose of placing the point ring 28 upon the needles of the machine I provide a manipulating mechanism 40 therefor, see Fig. I, which, per se, forms the subject of a copending application Serial No. 620,587, filed February 23, 1923, but on account of its importance in the present connection, I will nevertheless proceed to describe the same briefly. This mechanism in-

cludes a carrier for the point ring in the form of an arm 41 which is fast upon a rock shaft 42 journalled in a bracket 43 secured to the bed plate of the machine. One end of the 5 shaft 42 has fast to it a gear pinion 45 which is in mesh with an actuating sector 46 mounted for free movement upon a fixed stud 47 of the bracket 43. The sector 46, it will be noted, forms one arm of a bell crank 10 lever whose other extremity 48 carries a roller 49 designed to be influenced by a peripheral cam 50 of a cam drum 51. Said drum is mounted to rotate about a vertical axis 52 which depends from, and is secured 15 in an extension 53 of the bracket 43 previously referred to.

Suitable mechanism such as shown in the application mentioned in the preceding paragraph, is provided for controlling intermittent rotation of the cam drum 51, the latter having attached to its top, a ratchet wheel 55 adapted to be actuated by a pawl 56 on an oscillating arm 57 which is appropriately co-ordinated with the control mechanism. Thus when the cam drum 51 is rotated, the sector arm 46 is shifted in anti-clockwise direction, movement thus imparted to it being transmitted to the pinion 45 and causing downward swinging of the carrier 41 from the position illustrated in Fig. I to that of Fig. V with the point ring 28 poised above the needle cylinder. The point ring is temporarily locked to the carrier by means of a pin 58 which engages in registering aperture in the shell 31 of said ring. The locking pin 58 projects from one end of a lever 59 which is pivoted at 60 to the arm 41, said lever extending rearwardly of its pivot 60 and terminating in a laterally 40 turned end 61. When the carrier arm 41 is lowered, the end 61 of the lever 59 takes a position directly above a push rod 62 guided for vertical motion by the bracket 43 and arranged to be axially shifted through the 45 medium of a groove 63 of the cam drum 51, to effect, at the proper time, release of the point ring 28. The rod 62 has near its upper end, a lateral projection 65 adapted to engage a lug 66 on a wing 67 of the carrier arm 41 to lock the latter against movement 50 during fabric transfer simultaneously with the release of the point ring as above noted. A second push rod 68 with an adjustable extension 69 is provided to engage a lug 70 at 55 the end of an actuating arm 71 integrally formed with a yoke lever 72 which is fulcrumed at 73 to the carrier 41. In the ends of its extremities, the yoke lever 72 carries pins 74 which play within slots 75 at opposite sides of the carrier 41, and engage the upper edge of the shell 31 of the point ring 28 to depress the same from the position of Fig. V so that its points penetrate the fabric loops or stitches on the needles as best shown 60 in Fig. VI. The rod 68 is shifted by virtue

of the engagement of a roller 76 at its lower end with a third groove 77 in the cam drum 51.

In order to ensure proper registry and alignment of the needles relative to the 7 points of the point ring, the latter is initially placed upon its carrier 41 with the member 32 fully projected as indicated in Figs. I and V. As a consequence, when the point ring is applied, the member 32 will be 75 the first to engage the needles in the intervals between its outwardly extending radial projections 33, thereby, in continued movement of the ring, maintaining the needles and the points 29 in perfect registry in a 80 manner obvious from Fig. VI. In this way said points cannot possibly fail to penetrate the loops "S" of the terminal course of the fabric "F."

In accordance with my invention an additional preparatory step is practised before the fabric loops produced by the machine are actually shifted from the needles, namely, to displace the knitted fabric from 90 within the cylinder and to thrust it through the point ring. The means for accomplishing this includes a plunger 80 adapted to be actuated by a mechanism 81 which is only partly shown herein, but its operation will 95 be readily understood from another Patent No. 1,377,239 granted to me under date of May 10, 1921. Said mechanism 81 is connected through a link 82 to the push rod 68 previously mentioned, the latter thus serving as the actuating means therefor in lieu 100 of the handle shown in the patent supra.

At this juncture it will be convenient to describe the further function of the sleeve 36 which is to effect clamping of the fabric to the point ring 28 while the latter is being 105 separated, with the fabric thereon, from the needles, and this is accomplished simply by upward movement of said sleeve. As the sleeve rises from the position shown in Fig. VI, it first engages the fabric from beneath, incidentally clamping the same against the stripper 32 of the point ring 28, and thereafter lifts the ring bodily, all the while 110 maintaining the fabric clamped as noted, thereby preventing stripping the stitches 115 from the points 29. The extent of the upward motion of the sleeve is such as will cause complete dislodgement of the points 29 from the needles so that the ring may be thereafter safely removed without danger 120 of stitch dropping. The instrumentalities which determine the movements of the sleeve include (see Figs. I, II and III of the drawings) a pair of fingers 85 and 86 which are rigidly secured to a rock shaft 87 so that the angular relation between them is at all times maintained. The finger 85 is influenced by a cam projection or lug 87 on the periphery of the auxiliary pattern 125 drum 12 already referred to; while the 130

finger 86 is subject to a cam projection 88 likewise on the periphery of the cam drum, but in a different plane from that of the lug 87. In order to allow for alternate clearing of the fingers 85 and 86, the drum 12 is cut away as at 89 and 90 respectively (see Fig. II). Also fixed to the shaft 87 and preferably as an integral attachment of the finger 86, is a lever arm 91, which, through an interposed link 92 is connected to a pivot pin 93 extending through a longitudinal slot 94 in the tube 23 and projecting laterally from a slide bar 95 secured to and depending from the sleeve 36, see Fig. I. The slide bar 95 is slotted as at 96, Fig. I, so as to be guided in its vertical movement by penetrating studs 96^a fixed in the wall of the tube 23 and formed with appropriate heads to overlap the front of the bar. As a consequence of the foregoing provision, it will be observed that through rotation of the cam drum 12 in the direction of the arrow in Fig. II, the projection 87 will be the first to become active, thereby swinging the lever 85 and inducing corresponding motion in the shaft 87 and the lever 91, with the result that the sleeve 36 is drawn downwardly pulling with it the wedge annulus 25 and enlarging or dilating the terminal course of fabric loops on the knitting needles. This action is followed by engagement of the cam lug 88 with the finger 86 causing elevation of the sleeve 36, and, as a result, the clamping of the fabric to the point ring 28, and ultimately, dislodgement of the latter from the needles. The machine may be brought to a stop with the finger 86 resting upon the projection 88 to maintain the sleeve 36 in its elevated position to permit the removal of the point ring, or if further motion of the cam drum 12 should be necessary to other operations of the machine before stopping of the latter, I use a latch mechanism to function as a means for maintaining the sleeve 36 temporarily elevated. This latch mechanism includes a lever 97 of bell crank form pivoted for free motion at 98 to the outside of the tube 23. At one side, the vertical arm 99 of the lever 97 is concaved as at 100 to afford a cam edge for cooperating with the stud 93, so that as the latter is raised, the lever 97 is automatically swung aside to permit its passage. However, after the pin 99 clears the top of the arm 99, the lever 97 reassumes its original position and detains the stud 93 against descending. In this way therefore, the sleeve 36 and hence the point ring supported by it, is sustained in elevation so that the latter may be removed as before.

When the machine is to be restarted, it is obviously necessary that the sleeve 36, after removal of the point ring therefrom, be retracted to the normal position which it ordi-

narily occupies in the needle cylinder 1 as shown in Fig. VI. To this end, the arm 101 of the lever 97 is connected by means of a link 102 to some part of the machine which must be moved incidentally to the starting of the machine. This connection may be made as herein shown with mechanism 105 useful in transferring a new fabric, for example a stocking top, upon the machine for addition of the leg and foot. Said mechanism includes a swingable carrier 106, (similar to the carrier 41 for the point ring 28) fulcrumed at 107, to a fixed post 108 rising from the bed plate 3 of the machine; a latch member for locking a transfer device 109 (which for distinction from the point ring I will term, "quill ring") temporarily to the carrier 106 while the latter is being swung to a position above the needle cylinder; and a hand lever 110 for displacing the quill ring from its carrier when the fabric is to be shifted from the quills of the ring onto the needles of the machine. The link 102, it will be noted, is connected at its upper end, to a pin 111 projecting from the quill ring carrier. By this construction, therefore, as the quill ring is turned over to place a new web upon the needles of the machine, the link 102 is lifted, thereby causing the arm 99 of the bell crank latch lever 97 to be shifted beyond the province of the pin 93 and permitting the sleeve 36 and its appendages to drop under gravity influence to their normal positions.

I preferably arrange for the automatic withdrawal of the latch guard ring 22 after the completion of the knitting by the machine. The mechanism for doing this also forms part of the copending patent application to which I have already called attention hereinbefore. Said mechanism is only partly shown herein at 112.

In order to maintain the needle circle expanded during application of the point ring 28 to the cylinder 1, until the needles and points 29 are properly registered, it is necessary to hold the annulus 25 temporarily depressed. This function is performed by a second latch element 115 which operates upon the stud 93 in a manner very similar to that described of the latch lever 97. The said element 115 is in the form of a yoke fulcrumed, as at 116, to opposite sides of the tube 23, see Figs. I and II, and has a depending finger 117 adapted to swing into position above the stud 93 to temporarily detain the same, and accordingly the sleeve 36 and annulus 25, from rising under the action of the spring band 27. The opposite extremity 118 of the yoke 115 is connected by means of a link 119, with a pin 120 on the carrier arm 41 (Fig. I) for the point ring 28 so as to be tripped as the latter approaches the limit of its inward swing.

Means are also provided, of course, for

maintaining the web holders temporarily in the retracted position shown in the drawings during transfer so as to prevent them from interfering with removal of the fabric from the needles. Such means may be of any approved form suitable to the purpose.

Briefly described the sequence of operations involved in the transfer of knitted fabrics in accordance with my invention is as follows:

The quill ring 109 with a stocking top thereon is first placed upon the carrier 106, the latter next swung to position the quill ring over the needles of the machine, and the hand lever 110 subsequently depressed to transfer the stocking top from the quill ring to the knitting needles. When these initial steps are accomplished, the carrier 106 is retracted to withdraw the empty quill ring 109 from the needles and to permit removal of the quill ring for re-use. The needle latch guard 22 is thereupon lowered and the machine started to knit, in the well known manner, the stocking leg and foot, upon the completion of which the needles are automatically leveled by suitable means such as shown in my application No. 619,600, filed February 17, 1923, the web holders retracted, the latch guard withdrawn by the mechanism 112, and the wedge annulus 25 drawn downwardly by shifting of the sleeve 36 to spread the needles for the purpose of enlarging or dilating the terminal course of stitches held by the needles as shown in Fig. IV, the annulus being thereafter temporarily maintained in the depressed position by the latch 115. This is followed by rotation of the cam drum 51 which results in bringing about downward swinging of the carrier arm 41 to position the point ring 28 over the needles through actuation of the gear sector 46 and pinion 45. The entry of the points 29 into the needle circle is obviously facilitated by the preparatory spreading of the latter, and this is also true of the registry and alignment of the needles with the points in the interspaces of the member 32 of the ring. Just as the carrier 41 reaches the limit of its inward swing with the point ring in the position of Fig. V, the latch 115 is automatically tripped with the result that the sleeve 36, and with it the annulus 25 are freed to the influence of the spring band 27 thereby permitting contraction of the needle circle upon the ring 28. As a consequence, the needles fall back against the aligned points 29 and repose in this position during the remainder of the transfer operation. Further motion of the cam drum 51 causes, successively, release of the point ring from the carrier 41 and concurrent locking of the latter against movement by actuation of the vertical push 62 as previously explained; and depression of the ring 28 to penetrate its points through

the enlarged loops on the needles of the machine, simultaneously with displacement of the fabric bodily from within the needle cylinder and thrusting of the same into and through the point ring by actuation of the push rod 68; and final withdrawal of the various parts of the mechanism 40 to the normal position illustrated in Fig. I, leaving the point ring on the needles. The next shifting of the auxiliary pattern drum 12 brings the cam lug 88 into engagement with the finger 86 thereby effecting the elevation of the sleeve 36 and the dislodgement of the point ring 28, with the transferred fabric, from the needles.

In conclusion it is thought expedient in order to render clear the exact meaning of certain of the claims which follow, to point out that the sleeve 36 serves as a common actuator in bringing about the various steps essential to perfect transfer of the fabric from the needles of the machine to the points of the receiving point ring 28. Attention is also particularly called to the fact that in effecting separation of the points of the ring 29 from the needles of the machine, it is impossible for the ring to tilt angularly relative to the axis of the needle cylinder, or to become laterally or circumferentially displaced, thereby insuring positive maintenance of the vertical alignment of the points and the needles during their separation. The points and needles are thus safeguarded against bending and the fabric stitches or loops against distortion. Clamping of the fabric to the transfer ring, while important in preventing displacement of the loops or stitches during separation of the ring in effecting transfer of plain work, is doubly so in connection with the transfer of a completed stocking where the toe pocket, by reason of its interposition at one side of the tube and furthermore by reason of being necessarily compacted for accommodation in the transfer ring, has a tendency to force the loops at that side of the tube off the points of said ring. The latter contingency is therefore entirely offset by the clamping action of the sleeve 36.

Having thus described my invention, I claim:

1. In a knitting machine, the combination of a needle cylinder, a transfer ring with points for individually penetrating the loops of the terminal course of fabric on the needles, non-penetrating means for engaging said loops and preventing them from being withdrawn from the points incidentally to dislodgment of the ring from the needles during transfer.

2. In a knitting machine, the combination of a needle cylinder, a transfer ring with points for individually penetrating the loops of the terminal course of fabric on the needles, and non-penetrating means inde-

- 6 pendent of the ring for engaging said loops and preventing them from being withdrawn from the points incidentally to dislodgment of the ring from the needles during 5 transfer.
3. In a knitting machine, the combination of a needle cylinder, a transfer ring with points for individually penetrating the loops of the terminal course of fabric on the 10 needles, clamp means independent of the ring for holding said loops and preventing them from being withdrawn from the points incidentally to dislodgment of the ring from the needles.
- 15 4. In a knitting machine, the combination of a needle cylinder, a transfer ring with points for individually penetrating the loops of the terminal course of the fabric on the needles, and means for dislodging the ring 20 from the needles in effecting transfer, said means incidentally clamping the loops to prevent them from being withdrawn from the points.
- 25 5. In a knitting machine, the combination of a needle cylinder, a transfer ring, means for depositing the ring on the needles to receive fabric therefrom, separate means for dislodging the ring from the needles to facilitate its removal with the transferred 30 fabric, and means for automatically controlling the actuation of the depositing means and the dislodging means in the order specified.
- 35 6. In a knitting machine, the combination of a needle cylinder, a transfer ring adapted to be deposited upon the needles of the cylinder to receive fabric therefrom, means for dislodging the ring from the cylinder to facilitate its removal with the transferred 40 fabric, and automatic means instrumental in effecting restoration of said dislodging means to the normal retracted position upon restarting of the machine.
- 45 7. In a knitting machine, the combination of a needle cylinder, a transfer ring adapted to be deposited upon the cylinder to receive fabric therefrom, means for dislodging the ring with the transferred fabric from the cylinder, means for temporarily locking the 50 dislodging means in projected position to facilitate removal of the ring and fabric, and means for automatically tripping the locking means to permit return of the dislodging means to normal retracted position upon restarting the machine.
- 55 8. In a knitting machine, the combination of a needle cylinder, a point ring adapted to be deposited upon the cylinder to receive fabric therefrom, means for dislodging the 60 point ring with the transferred fabric from the cylinder, means for temporarily maintaining the dislodging means projected to facilitate removal of the point ring and fabric, means for applying a quill ring to 65 the cylinder for transfer of a new fabric to the machine, and means coordinated with the said applying means instrumental during movement of the latter in effecting restoration of the aforementioned dislodging means to the normal retracted position. 70
9. In a knitting machine, the combination of a needle cylinder, a point ring adapted to be deposited upon the cylinder to receive knitted fabric therefrom, means for engaging the ring from beneath to lift it with the transferred fabric clear of the needles, locking means for temporarily maintaining said dislodging means elevated to facilitate removal of the ring with the transferred fabric, a swingable carrier for applying a quill ring to the cylinder for transfer of a new fabric to the machine, and connections whereby the locking means aforesaid is tripped during movement of said carrier to permit the dislodging means to resume its 80 normal retracted position. 85
10. In a knitting machine, the combination of a needle cylinder, a point ring adapted to receive knitted fabric from the needles, means for engaging the ring from beneath during transfer of the fabric thereto to lift the same clear of the needles, devices for temporarily maintaining said means in elevated position to permit removal of the ring, a trip associated with said devices, a transfer ring for transferring fabric to the needles, a movable carrier for the transfer ring, and connections co-ordinating the carrier and the trip whereby the means aforesaid is restored to retracted position upon 90 movement of said carrier in the course of transferring fabric to the needles. 95
11. In a knitting machine, the combination of a needle cylinder, a point ring adapted to receive knitted fabric from the needles, instrumentalities for enlarging the fabric loops to facilitate introduction thereinto of the points of the ring aforesaid, and common means for first actuating said loop enlarging instrumentalities, then stripping the fabric loops from the needles, and finally lifting the ring, with the transferred fabric, 100 clear of the needles. 105
12. In a knitting machine the combination of a needle cylinder, a point ring adapted to receive knitted fabric from the needles, a wedge annulus concentrically disposed within the cylinder for spreading the needles to enlarge the fabric loops in preparation for the points of the ring aforesaid, and a sleeve independently shiftable within the cylinder and operative when moved in one direction, to actuate the wedge annulus, and when moved in the opposite direction to first strip the fabric loops from the needles and finally to lift the ring, with the fabric, 110 clear of the needles. 115
13. In a knitting machine the combination of a needle cylinder, a point ring adapted to receive knitted fabric from the needles, a 120

- wedge annulus concentrically disposed within the cylinder for spreading the needles to enlarge the fabric loops in preparation for the points of the ring aforesaid, a sleeve independently shiftable within the cylinder and operative when moved in one direction, to actuate the wedge annulus, and when moved in the opposite direction to first strip the fabric loops from the needles, and finally to lift the ring, with the fabric, clear of the needles, and devices for automatically actuating the sleeve to perform its allotted functions in the order named. 5
14. In a knitting machine the combination of a needle cylinder, a point ring adapted to receive knitted fabric from the needles, a wedge annulus concentrically disposed within the cylinder for spreading the needles to enlarge the fabric loops in preparation for the points of the ring aforesaid, a sleeve independently shiftable within the cylinder and operative when moved in one direction, to actuate the wedge annulus, and when moved in the opposite direction to first strip the fabric loops from the needles and finally to lift the ring, with the fabric, clear of the needles, and devices for automatically actuating the sleeve to perform its allotted functions in the order named. 10
15. In a knitting machine, the combination of a needle cylinder, a point ring adapted to receive knitted fabric from the needles, a wedge annulus concentrically disposed within the cylinder for spreading the needles to enlarge the fabric loops in preparation for the points of the ring aforesaid, a sleeve independently shiftable within the cylinder and operative when moved in one direction, to actuate the wedge annulus, and when moved in the opposite direction to first strip the fabric loops from the needles and finally to lift the ring, with the fabric, clear of the needles, and devices for automatically actuating the sleeve to perform its allotted functions in the order named, including a rotary cam drum, a bell crank lever with its extremities adapted to be alternately engaged by cams on said drum, and interposed link connections for imparting the movements of the bell crank lever to the sleeve. 20
16. In a knitting machine, the combination of a needle cylinder, a point ring, means to deposit the point ring on the cylinder to receive knitted fabric therefrom, ejecting means for thrusting the fabric from within the cylinder and through the ring preparatory to transfer, separate means for dislodging the ring from the cylinder to facilitate its removal with the transferred fabric from the machine, and means for automatically controlling actuation of the ring depositing means, the fabric ejecting means, and the ring dislodging means in the order mentioned. 25
17. In a knitting machine, the combination of a needle cylinder, a point ring adapted to receive knitted fabric from the needles, means for enlarging the fabric loops to facilitate introduction thereinto of the points of the point ring, means for thrusting the fabric bodily from the cylinder through the transfer ring, means for advancing the fabric loops from the needles, clamping the fabric to the ring, and at the same time lifting the ring clear of the needles, and mechanism for controlling the various functions aforesaid in the order named. 30
18. In a knitting machine, the combination of a needle cylinder, a point ring adapted to receive fabric from the needles, means for spreading the needle circle to facilitate reception of the ring and to enlarge the fabric loops in preparation for the points of said ring, and means operative incidentally to deposit of the ring upon the cylinder to effect release of the needles for repose against the aligned points during transfer of the fabric. 35
19. In a knitting machine, the combination of a needle cylinder, a point ring adapted to receive knitted fabric from the needles, means for spreading the needle circle to facilitate reception of the ring and to enlarge the fabric loops in preparation for the points of said ring, a movable carrier for positioning the ring to align its points with the needles, and means coordinated with the carrier for automatically effecting release of the needles for repose against the aligned points during transfer of the fabric. 40
20. In a knitting machine, the combination of a needle cylinder, a point ring adapted to receive knitted fabric from the needles, a spring influenced wedge annulus concentrically disposed within the needle cylinder, means for shifting the wedge annulus to spread the needle circle for the purposes of facilitating introduction of the ring and enlarging the fabric loops in preparation for the points of said ring, latch mechanism for locking the shifting means aforesaid to maintain the needles temporarily spread, a movable carrier for positioning the ring to align its points with the needles and incidentally operative in automatically tripping the latch mechanism thereby to release the needles for repose against the aligned points during transfer of the fabric. 45
21. In a knitting machine, the combination of a needle cylinder, means for spreading the needle circle to enlarge the loops of fabric thereon in preparation for transfer, 50
- concurrently operated means for tripping the locking means aforesaid to enable the dislodging means to resume the normal retracted position for restarting of the machine. 55

- means for depositing a transfer ring upon the cylinder with its points penetrating the dilated fabric loops, means operative incidentally to actuation of the depositing means to release the needles for repose 5 means to release the needles for repose against the points of the ring, means for dislodging the ring from the cylinder to facilitate its removal with the transferred fabric, and means to control actuation of 10 the ring depositing means and the ring dislodging means in the order specified.
22. In a knitting machine, the combination of a needle cylinder, means for spreading the needle circle to enlarge the loops of 15 fabric thereon in preparation for transfer, means for depositing a transfer ring upon

the cylinder with its points penetrating the dilated fabric loops, means operative incidentally to actuation of the depositing means to release the needles for repose 20 against the points of the ring, means to eject the knitted fabric from within the cylinder and through the ring, means to dislodge the ring from the cylinder to facilitate removal with the transferred fabric, and means to 25 control actuation of the ring depositing means, the fabric ejecting means, and the ring dislodging means in the order specified.

In testimony whereof, I have hereunto signed my name at Philadelphia, Pennsylvania, this 7th day of May 1923.

LOUIS N. D. WILLIAMS.
